UNITED STATES PATENT OFFICE

2,428,534

CLEAN SWEEP COUNTER AND STOOL
CONSTRUCTION

Ira O. Stelzer, Wooster, Ohio

Application February 8, 1946, Serial No. 646,233

6 Claims. (Cl. 155—123)

1

This invention relates to restaurant furniture, more particularly to a clean sweep counter and stool construction. My novel construction facilitates sweeping and mopping of the restaurant floor thereby resulting in time saving and promotion of sanitary conditions.

It is a particular object of my invention to provide an inclined shield including supporting features or brackets for supporting an upright standard or support for the stool seat. The inclined shield guides or directs crumbs or the like which fall from the counter or the person using the counter and stool.

It is an object of my invention to provide an upright standard or support having a bent portion intermediate the ends thereof. The lower end of the standard being supported an ample distance above the floor line to provide for ready access of a broom or mop when cleaning the restaurant floor.

It is also an object of my invention to provide a bracket having arms arranged at an acute angle to each other whereby one arm may be secured to the floor and the other arm constitute a base to which the inclined shield may be secured, whereby the inclined shield forms a closely jointed connection or contact between the floor and the front portion of the counter.

It is also an object of my invention to provide a fixed relation between the inclined shield and the front portion of the counter thereby maintaining close contact between the counter and the shield.

It is also an object of my invention to provide a footrest comprising a rail extending transversely and horizontally below the bent portion of the standard and suitably spaced from both the floor and the inclined guiding shield.

It is also a further object of my invention to provide means whereby the lower end of the standard is provided with a single fastening means passing through said standard and to a place of engagement below the surface portion of the floor.

Further objects and advantages will be revealed in connection with the detailed description of the accompanying drawings which form a part of my specification.

Figure 1 is a view of my novel clean sweep construction in front elevation.

Figure 2 is a view of my construction as seen from the top thereof.

Figure 3 is a view in vertical transverse section showing the relation of the stool, inclined shield, counter, footrest and floor fastening means, and

2

Figure 4 is a view of a fragment of my invention shown in perspective as seen from the rear thereof.

The drawings are merely illustrative of my invention and not definitive thereof except as pointed out in the subject matter claimed herein.

The reference characters identify the parts of my invention in both the specification and the drawings.

10 The floor 1 supports the counter and stool construction. The counter 2 is maintained in position on the floor by a strip of material 3 extending the full length of the counter thereby preventing any horizontal movement in any direction. In this connection it is to be observed that brackets having arms at right angles to each other (not shown) could be used in lieu of the strip 3. The strip 3 is secured to the floor by suitable means and may also be secured to the 15 front wall 4 of the counter if desired. The top 5 of counter is provided with a bead 6 along its forward edge.

15 The upright standard or support 7 is provided with a bent portion 8 located intermediate the ends thereof. The upper end portion 9 is provided with a socket 10 adapted to receive a supporting means 11 on the stool seat 12 thereby supporting the seat 12 rotatably on the standard 7. The lower end 13 of the standard extends 20 through openings 14 and 15 of the bracket arms 16 and the inclined shield or ramp 17. The bracket 18 is provided with a short arm 19 at an acute angle to the arm 16. The short arm of the bracket and the lower end of the standard 25 are secured to the floor by a single means passing therethrough comprising a bolt 20. The long arm 16 of the bracket forms an inclined support for the shield 17 which is secured to the long arm by suitable lag bolts 21 as clearly displayed in Figure 3.

30 It is noted that the lower end 13 of the standard 7 is flattened and provided with an aperture to receive the bolt 20. It appears to be clear that the lower end 13 of the standard would not need 35 to be flattened but on the contrary the contemplated tubular standard could be provided with a plug located within the end thereof and both the plug and tubular portion apertured to receive a bolt such as 20. It is observed that this modified structure is not shown on the drawings but is merely contemplated as an obvious variation of the construction displayed in the drawings, in 40 Figs. 3 and 4.

45 The section 22 of the standard located below the bend 8 thereof is provided with a footrest 23

secured transversely and horizontally relative to said standard. A saddle 24 is provided for each section 22 and is provided with a recess on its upper portion to receive the rail. The rail and saddle as well as the section 22 are provided with aligned apertures to receive the carriage bolt 25 provided with a nut 26 whereby the rail is secured in a suitably spaced position from both the floor 1 and the inclined shield 17.

It is contemplated that the standard 1 may be made of tubular material but it is obvious that solid materials may be used if so desired.

The main support for the standard is provided by the bracket arm 16. The arm and inclined shield are provided with openings to receive the standard and to support the same in spaced relation from the floor thereby providing ample space for the operation of the mop, broom or other implement for cleaning the floor and the inclined shield.

It is noted that the angle between the arms 16 and 19 is substantially 45° but it may be desired to increase this angle and thereby increase the pitch of the inclined shield or ramp 17. The shield or ramp is preferably made of sections of wood, but may be made of other suitable materials, such as, metal or plastic composition of any suitable variety.

Figure 1 discloses an ordinary floor construction supported by joists 30. The joists are engaged transversely by a strip 31 which receives the bolts 20 having the nuts 32. This construction clearly indicates that the standard 1 and the brackets 18 are firmly secured to the floor construction.

When assembling the standard 1 with the bracket 18 the lower end may be inserted through the openings 14 and 15 before being flattened; then the end may be flattened if desired, as shown in Figures 3 and 4.

Triangular closure pieces (not shown) may be provided for the open ends formed by the inclined guide in conjunction with the front of the counter and the floor. Such pieces may be secured in position by any suitable fastening means.

Having fully described my invention, including the operation thereof, what I claim is:

1. A clean sweep counter and stool construction, especially adapted for use in restaurants, lunch rooms and the like; said construction comprising a counter, a stool and a support therefor, said counter being provided with means to prevent horizontal movement in any direction, said stool having an upright support defining a socket in its upper end for a rotatable stool seat, said upright support having a bent portion intermediate the ends thereof, means on the lower end of the upright support for securing it to a floor, in combination with an inclined bracket arm forming a supporting means for said upright support, said inclined bracket arm constituting a base for an inclined shield secured thereto, said shield extending at a suitable angle from the floor to the counter.

2. The construction set forth in claim 1 in which the upright support is provided with a transversely and horizontally arranged footrest suitably spaced from the inclined shield.

3. The construction set forth in claim 1, in

which the lower end of the upright support and the lower arm of the bracket are provided with fastening means passing therethrough for securing them to the floor.

5. The construction set forth in claim 1, in which both the bracket and the inclined shield are provided with openings receiving the lower end portion of the upright support to aid in supporting the same.

10 6. In restaurant or the like furniture, said furniture comprising a combined counter and stool construction, said counter being secured against horizontal movement in all directions, in combination with an upright stool construction suitably spaced from the front of said counter, said stool construction comprising an upright support having in its upper end a socket whereby a stool seat may be rotatably supported thereon, the lower end of said upright support being provided with means whereby it may be fixedly se-

20 cured in a suitably spaced distance in front of said counter, in further combination with a bracket having a horizontal arm and an inclined arm, said inclined arm embracing said upright support and sustaining the same in supported condition, said inclined arm extending from a position beyond the lower end of said upright support to a position in close proximity of an upright portion of said counter, said inclined arm constituting a base for supporting an inclined guiding shield secured thereto, said inclined guiding shield being wide enough to extend from the floor to an upright portion of the counter.

25 7. In furniture construction for restaurants, lunch rooms and the like, comprising a combined counter and stool construction arranged in suitable fixed relation, said stool having an upright support having a bent portion intermediate the

30 ends thereof, the lower section of said upright support being provided with a transversely and horizontally arranged footrest, in combination with a bracket having a short arm, adapted to be secured to a floor, and a long arm extending

35 8. In furniture construction for restaurants, lunch rooms and the like, comprising a combined counter and stool construction arranged in suitable fixed relation, said stool having an upright support having a bent portion intermediate the ends thereof, the lower section of said upright support being provided with a transversely and horizontally arranged footrest, in combination with a bracket having a short arm, adapted to be secured to a floor, and a long arm extending

40 9. In furniture construction for restaurants, lunch rooms and the like, comprising a combined counter and stool construction arranged in suitable fixed relation, said stool having an upright support having a bent portion intermediate the ends thereof, the lower section of said upright support being provided with a transversely and horizontally arranged footrest, in combination with a bracket having a short arm, adapted to be secured to a floor, and a long arm extending

45 10. In furniture construction for restaurants, lunch rooms and the like, comprising a combined counter and stool construction arranged in suitable fixed relation, said stool having an upright support having a bent portion intermediate the ends thereof, the lower section of said upright support being provided with a transversely and horizontally arranged footrest, in combination with a bracket having a short arm, adapted to be secured to a floor, and a long arm extending

50 11. In furniture construction for restaurants, lunch rooms and the like, comprising a combined counter and stool construction arranged in suitable fixed relation, said stool having an upright support having a bent portion intermediate the ends thereof, the lower section of said upright support being provided with a transversely and horizontally arranged footrest, in combination with a bracket having a short arm, adapted to be secured to a floor, and a long arm extending

55 12. In furniture construction for restaurants, lunch rooms and the like, comprising a combined counter and stool construction arranged in suitable fixed relation, said stool having an upright support having a bent portion intermediate the ends thereof, the lower section of said upright support being provided with a transversely and horizontally arranged footrest, in combination with a bracket having a short arm, adapted to be secured to a floor, and a long arm extending
